UNITED STATES PATENT OFFICE.

GEORGE P. HAYES, OF ROCHESTER, NEW HAMPSHIRE.

DESIGN FOR A SCARF-PIN.

SPECIFICATION forming part of Design No. 17,845, dated November 1, 1887.

Application filed September 8, 1887. Serial No. 249,178. Term of patent 7 years.

To all whom it may concern:

Be it known that J. GEORGE P. HAYES, a citizen of the United States, residing at Rochester, in the county of Strafford, State of New Hampshire, have invented and produced a new and original Design for Scarf-Pins, of which the following is a full, clear, and exact description, reference being had to the accompanying drawing, forming a part of this specification, in which the figure is a front elevation representing my newly-designed scarf-pin.

The leading feature of my design consists in the representation of a pair of ordinary laster's pinchers, A, with their jaws z closed, and having letter-like scrolls arranged vertically between the handles x thereof. Pendant from one of the jaws z appears the tack-

hammer m, common to pinchers of this description.

The pin y of the scarf-pin is shown as projecting horizontally and centrally from the joint of the pinchers between the handles x at the rear of letter-like scrolls.

Having thus explained my design, what I claim is—

The design for a scarf pin herein shown and described, the same consisting, essentially, of the representation of a pair of laster's pinchers with letter-like scrolls arranged vertically between the handles thereof.

GEORGE P. HAYES.
